CHRISTOPHER W. CAREY AND CHESTER S. LEONARD, OF PHILADELPHIA, PENNSYLVANIA, ASSIGNORS TO QUAKER CITY CLOCK ADVERTISING CO., A CORPORATION OF DELAWARE.

APPARATUS FOR DISPLAYING ADVERTISING MATTER.

1,097,583.

Specification of Letters Patent.

Patented May 19, 1914.

Application filed August 8, 1912. Serial No. 714,080.

To all whom it may concern:

Be it known that we, CHRISTOPHER W. CAREY and CHESTER S. LEONARD, citizens of the United States, residing at Philadelphia, 5 in the county of Philadelphia and State of Pennsylvania, have jointly invented certain new and useful Improvements in Apparatus for Displaying Advertising Matter, of which the following is a specification.

- 10 This invention has relation to apparatus for displaying advertising matter, wherein at predetermined intervals, an electro-magnet is energized by the closing of a circuit to permit to operate a motor, which in 15 turn revolves a carrier for consecutively displaying advertising cards and refers more particularly to the apparatus described and claimed in United States Letters Patent, No. 805,786, and dated November 28, 1905.
- 20 It has been demonstrated in practice, it is essential among other things, to the commercial value of the apparatus above referred to, that a perfect circuit-closer be present for periodically completing and 25 breaking the circuit through the electro-magnet. It has also been proven, that it is essential to energize the electro-magnet in advance of the operating of the motor, which drives the carrier containing the display cards. Practice has also demonstrated, 30 that it is detrimental to the apparatus to revolve the carrier rapidly and suddenly stop its movement. Considerable difficulty has also been experienced in securing a carrier 35 for the display cards of such construction that the cards be centralized with respect to the carrier during movement thereof in contra-distinction from being moved laterally or sidewise, thereby jamming.
- 40 It is one object of the present invention to overcome the above recited disadvantageous features and to provide apparatus that is reliable in operation and comparatively inexpensive to manufacture.
- 45 A further object of the present invention resides in the providing of a circuit-closer of cam-like construction with which co-
operates a gravity contact.

A further object of the present invention 50 resides in the providing of a specially designed contact so arranged and constructed that the mechanical-electric motor for operating the chain of display cards be permitted to operate only after the electro-mag-

net has been energized and the transmission 55 medium be released for operating.

A still further object of the present invention resides in the providing of a specially designed carrier for a chain of advertising cards of such construction that the individual cards in moving are maintained centrally of the carrier in contra-distinction from moving sidewise thereon and jamming.

Other objects of the present invention resides in the novel arrangement and construction of parts which are particularly designed for the out-door display of advertising cards and in so arranging the parts that ready access may be had thereto for interchangeable connection of the various devices.

With these and other objects in view, the invention consists of the improvements hereinafter described and finally claimed.

The nature, characteristic features and scope of the invention will be more fully understood from the following description taken in connection with the accompanying drawings, forming part hereof and in which:

Figure 1, is a perspective view of the advertising apparatus embodying the invention, Fig. 2, is a view in front elevation, with certain of the casing parts removed, illustrating the interior arrangement of the apparatus, Fig. 3, is a view in elevation, drawn to an enlarged scale, of the clock movement 80 shown at the left-hand side of Fig. 2, Fig. 4, is a perspective view of the circuit-closer shown in Fig. 3, Fig. 5, is a view in elevation of the side of the circuit-closer opposite to that shown in Fig. 3, Fig. 6, is a view in 90 front elevation of the carrier for supporting the chain of advertising cards shown in Fig. 2, Fig. 7, is a view in section taken upon the line 7—7 of Fig. 6, Fig. 8, is a top or plan view of the carrier operating mechanism shown at the right-hand side of Fig. 2, Fig. 9, is a view in section taken upon the line 9—9 of Fig. 8, and Fig. 10, is a fragmentary view, in elevation, of certain of the parts shown in Fig. 9, but in a different position.

The advertising apparatus, about to be described, is primarily intended for outdoor display and to that end, practice has demonstrated that specially designed parts 105 are essential to the successful operation of the apparatus. As shown in Fig. 1, the casing 1, is preferably of sheet metal construc-

tion. Such a structure is practical for outdoor use and preserves the contents of the casing against attack by the elements. The casing 1, is shown as being comparatively narrow in comparison to its height and as being provided with hinged covers 2, and 3, at suitable places. The casing 1, is further provided with a time piece 4, and preferably an incandescent lamp and reflector 5, for illuminating the face thereof. Immediately below the time piece, the casing 1, is provided with an opening 6, before which are calculated to appear the various individual cards, bearing advertisements, which go to make up the endless chain of cards 7, see Fig. 2. Above the opening 6, is arranged a reflector 8, preferably containing incandescent lamps for illuminating the cards as they appear before the opening 6. Taking up now the parts within the casing 1, the card operating mechanism is shown as being located well toward the top of the casing and immediately back of the time piece 4. Supported upon suitable brackets 9, is a horizontally disposed plate 10, see Figs. 2, 8, and 9. As shown in Fig. 8, this plate 10, is centrally cut-away as at 11, to accommodate the rotatable carrier 12. The rotatable carrier 12, is arranged centrally of the plate 10, and is journaled thereto as at 13, so that in its rotation, the endless chain of cards 7, passes in the direction of the arrow, see Fig. 2, up through the opening 11, of the plate 10. As shown in Fig. 2, an electric motor A, is present upon the plate 10, adjacent the right-hand side of the carrier 12, which electric motor is operatively connected through the instrumentality of a transmission medium B, with said carrier. Shown at the left-hand side of the carrier 12, and as being supported by the plate 10, is a clock movement C. Mounted upon a moving part of the clock movement is a circuit-closer for periodically completing and breaking a circuit through an electro-magnet for alternately releasing and stopping the transmission medium independently of the starting and stopping of the electric motor.

A description will first be given of the circuit-closer, reference being had more particularly to Figs. 1, to 5, inclusive. The shaft 14, of the clock movement C, which shaft is operative through the instrumentality of the pendulum 15, in connection with the weight 15^a, has fixed thereto the circuit-closer 16, of the invention, which in operation moves in the direction of the arrow in Figs. 3, and 4. The circuit-closer 16, which is cam-like in construction, is shown as comprising a pair of disks arranged side by side upon the shaft 14, and as being adjustably connected together concentrically considered as at 17, see Fig. 5. Of these two disks, the disk 18, is of insulating material, preferably

fiber, and the disk 19, is of conducting material, preferably brass. The peripheries of the disks 18, and 19, in effect form a cam face. Having pivotal relation as at 20, with the frame of the clock movement C, is a gravity contact strip 21. As clearly shown in Fig. 3, the pivotal point 20, of this contact strip is arranged in a plane considerably above that of the highest point of the circuit-closer 16, so that the contact member 21, through gravity rests upon some part of the cam face of said circuit-closer at all times. The contact strip 21, as shown in Fig. 4, is of a width equal to the width of the combined parts 18, and 19. The parts 18, and 19, are cut-away as at 22, and 23, to provide a step down arrangement for the gravity contact strip, of which the part 22, of the disk 18, is arranged in advance of the part 23, of the disk 19. Thus, in rotation of the circuit-closer 16, in the direction of the arrow in Figs. 3, and 4, the contact strip 21, normally rests upon the disk 18, of insulated material during which time the motor A and transmission medium B, are inoperative. When the high portion of the disk 18, leaves the free end of the contact strip 21, said contact strip gravitates to and rests upon the high part 24, of the disk 19, and remains in contact therewith for a period of time in proportion to the adjustment secured by the parts 17, see Fig. 5. The contacting of the contact strip 21, with the disk 19, energizes the electro-magnet D, from batteries 26, through conductor 25, to shaft 14, disk 19, contact strip 21, conductor 27, to electro-magnet D, the return circuit being by conductor 28, to batteries 26.

The energizing of the electro-magnet D, releases mechanism about to be described for permitting to operate the transmission medium B. In this connection it will be noted that the electro-magnet is energized independently of and considerably in advance of the energizing of the electric motor A. Referring now more particularly to Figs. 8, 9, and 10, said transmission medium B, is shown as being supported between suitable uprights 29. Shown as having pivotal relation between and insulated from the uprights 29, is a bar 30. Having fixed relation with the bar 30, as at 31, is a forwardly extending metallic rod 32, the free end of which terminates in a depending generally hook-like extension 33, the purpose of which will presently appear. This rod 32, carries a block of insulating material 34, extending laterally from which is a metallic pin 35. Also fixed to the pivotal bar 30, is an armature 36, which is alternately caused to advance toward or recede from the electro-magnet D, as the magnet is energized or de-energized. In order to properly support the free end of the rod 32, the same is connected by means of a rod 37, with, but insulated

from the armature 36. Shown as mounted upon one of the uprights 29, is a contact strip 38, which is insulated therefrom and laterally extending so as to overlie the rod 32. Leading from the batteries 39, to the pivotal bar 30, is a conductor 40, and leading from the contact strip 38, to one pole of the electric motor A, is a conductor 41, the opposite pole of the electric motor A, being connected by a return lead 42 to the batteries 39. The batteries 26, and 39, are arranged in multiple series, as such arrangement is particularly adapted for the operation of applicants' devices. The transmission medium B, which is directly influenced by the above described connections, is primarily made up of a series of intermeshing wheels of such dimensions that they coöperate to transmit a suitable speed to the shaft 43, to which is fixed the carrier 12. These intermeshing wheels in turn are divided into two groups, one group for directly operating the shaft 43, and the other group for operating a speed governor 44, which speed governor 25 is permitted to operate by the raising of the end 33, of the rod 32. Taking up now the first series of wheels the shaft 45, is provided with a cog wheel 46, and a gear wheel 47. The gear wheel 47, meshes with the cog wheel 48, of the electric motor A, see Fig. 8. The gear wheel 47, serves to operate a train of gear wheels connecting with the governor 44. In turn, the cog wheel 46, meshes with a gear wheel 49, mounted upon a shaft 50. The shaft 50, has secured thereto an escapement wheel 51, notched as at 52, to correspond with the number of card receiving faces upon the carrier 12, four being shown in the drawings. The direction of rotation 40 of the escapement wheel 51, is in the direction of the arrow in Fig. 9, and the hereinbefore described pin 35, carried by the rod 32, normally rests within one of the notches 52, of said escapement wheel. In this position the rod 32, is free of and located below the contact strip 38. When a contact is made between the disk 19, of the circuit closer 16, and the gravity contact member 21, to energize the electro-magnet D, the rod 50 32, is moved around its pivotal point by virtue of the armature 36, being drawn toward the electro-magnet D, which movement raises the pin 35, from its complementary notch 52, of the escapement wheel 51. At 55 the same time a contact is made between the rod 32, and contact strip 38, which contact energizes the electric motor A, through conductor 41, and sets in operation the above described sets of gear wheels and through 60 the instrumentality of gear wheel 53, which is in mesh with the gear wheel 49, sets in motion the shaft 43, together with the carrier 12. By referring now to Fig. 10, it will be seen that during the above operation the 65 pin 35, rides upon the periphery of the es-

capement wheel 51. As the pin 35, rides upon the periphery of the escapement wheel, the rod 32, cannot gravitate but is held in constant contact with the strip 38. Thus, as the movement of the circuit-closer 16, is relatively slow, a long contact is maintained between the batteries and the electro-magnet D, and a continuance of current is furnished the electric motor A, by reason of the escapement wheel in contra-distinction to a short quick current supply. Thus, a sure and positive operation of the electric motor A, insures an accurate and steady movement of the carrier 12. As the next succeeding notch 52, of the escapement wheel, comes in alinement with the pin 35, the rod 32, gravitates, thereby breaking electrical connection between the parts.

A description of the retarding wheels of the transmission medium B, will now be given. The shaft 54, has a cog wheel 55, which meshes with the before described gear wheel 47. This shaft 54, in turn is provided with a gear wheel 56, which meshes with a cog wheel 57, on a shaft 58. The shaft 58, in turn is provided with a gear wheel 59, meshing with a cog wheel 60, on the shaft 61, which carries and has fixed thereto, the speed governor 44. When the electromagnet D, is energized, thereby raising the rod 32, the end 33, of said rod is moved free of the speed governor 44, permitting it to move in the direction of the arrow in Fig. 9, through the instrumentality of the last-mentioned intermeshing wheels. When the electromagnet D, is deenergized the motor A, continues to operate so long as the pin 35, is in engagement with the periphery of the disk 51. When, however, one of the notches 52, of said disk comes opposite the pin 35, said pin 100 drops therein, whereupon the rod 32, gravitates to its normal position, electrical connection to the motor is broken and it stops, and the governor 44, abuts against the end 33, of the rod 32, thus effectually stopping 105 any momentum of the transmission medium B, as a whole.

Taking up now the carrier 12, which is fixed to the shaft 43, the same is shown as comprising a pair of end plates 62, connected together by means of horizontally extending rods 63. These rods penetrate the plates 62, and may be secured thereto by means of screws 64, see Fig. 8. Each end plate 62, is of circular configuration, generally speaking, 115 and is provided on its inner face with a generally rectangular member forming a ledge 65, for supporting the chain of cards 7. In the drawings, the faces of the ledge 65, are four in number. Between each card receiving face 65, and the peripheries of the end plates a generally convexed surface 66, is present and between the ledges 65, and the plate centers, a spider-like construction 67, is present, in order to provide lightness of 120 125 130

structure. In practice, the generally curved surfaces 66, serve to guide the cards of the chain 7, toward the center of the carrier. In other words the curved surfaces 66, of the 5 plates 62, prevent the cards from shifting endwise so as to create a jamming of the carrier parts.

What we claim is:

1. A carrier for advertising apparatus of 10 the class described comprising rotatably supported spaced plates, each plate being provided with a generally polygonal ledge for supporting a chain of cards, the inner face of each plate adjacent said ledge being convexly curved from the juncture point of said ledge with said plate outwardly to the plate periphery.
2. A carrier for advertising apparatus of 20 the class described comprising rotatably supported plates, each plate being provided with a generally polygonal ledge for supporting a chain of cards that part of said plate adjacent each supporting face of the ledge being convexly curved throughout the length 25 of each face and from the juncture point of said ledge with said plate outwardly to the periphery of the plate and horizontally disposed tie rods connecting the ledges of said plates.
3. A carrier for advertising apparatus of 30 the class described comprising a pair of rotatably supported plates each provided with a generally polygonal ledge having card receiving faces that part of each plate adjacent said ledge being convexly curved from the juncture point of said ledge with said plate outwardly to the plate periphery, a bearing for each plate, and a spider interposed between said ledge and said bearing.
4. In apparatus of the class described the 40 combination of an intermittently driven shaft, a carrier fixed thereto consisting of spaced plates each plate being provided with

a generally polygonal card supporting ledge upon its inner face, the inner face of each 45 plate being convexly curved from the periphery thereof to the juncture point of said ledge with said plate, a chain of cards, a medium for operating said carrier shaft and means for alternately releasing and stopping 50 said medium.

5. In apparatus of the class described the combination of a horizontally disposed supporting frame having a generally rectangular central opening therein, bearings carried 55 by said frame, a horizontally disposed shaft rotatably mounted in said bearings, a carrier consisting of spaced circular plates fixed to said shaft each plate having a generally polygonal card receiving ledge and a convexly curved surface extending from the juncture point of said ledge with said plate to the periphery of said plate, a chain of cards for the carrier, which carrier and cards in rotation move through the opening 65 in said frame, a medium carried by said frame for intermittently operating said shaft and means for alternately releasing and stopping said medium.

6. A carrier for clock controlled advertising apparatus comprising a shaft, a pair of circular plates carried by said shaft each of 70 said plates being provided with a generally polygonal card receiving ledge that part of said plates between said card receiving ledge 75 and the periphery of the plates being convexly curved and horizontally disposed rods connecting said plates.

In testimony whereof, we have hereunto signed our names.

CHRISTOPHER W. CAREY.
